UNITED STATES PATENT OFFICE.

WILLIAM J. HEFFERNAN, OF LYNN, MASSACHUSETTS, ASSIGNOR OF FIFTY-SEVEN ONE-HUNDREDTHS TO HORACE R. BURDICK, NICHOLAS J. MOONEY, EDWARD L. MORRIS, WILLIAM D. ROBERTSON, AND WALTER M. TOMLINSON, ALL OF BOSTON, MASSACHUSETTS; SAID MORRIS ASSIGNOR TO SAID BURDICK, MOONEY, ROBERTSON, AND TOMLINSON.

BOOT AND SHOE HEELING MACHINE.

SPECIFICATION forming part of Letters Patent No. 252,105, dated January 10, 1882.

Application filed August 16, 1881. (No model.)

To all whom it may concern:

Be it known that I, WILLIAM J. HEFFERNAN, of Lynn, in the county of Essex and State of Massachusetts, have invented certain Improvements in Boot and Shoe Heeling Machines, of which the following is a specification.

This invention relates to heeling-machines employing nail-holders arranged in gangs and corresponding gangs of drivers supported by a rotary head or frame adapted to bring the gangs successively over the boot or shoe supporting last under the driver-operating mechanism.

The invention consists in certain improvements which I will now proceed to describe.

Of the accompanying drawings, forming a part of this specification, Figure 1 represents a side elevation of a machine embodying my invention. Fig. 2 represents a front elevation of the same. Fig. 3 represents a perspective view of a portion. Fig. 4 represents a section on line $x-x$, Fig. 2. Figs. 5 and 6 represent respectively top and side views of one of the gangs of nail-holders. Figs. 7 and 8 represent sections on line $z-z$, Fig. 5, the jaws being in different positions. Figs. 9 and 10 represent end views of the nail-holder, the jaws being in the positions shown in Figs. 7 and 8. Fig. 11 represents a section on line $x'-x'$, Fig. 7. Fig. 12 represents a bottom view of one of the nail-holders, showing a spring for inclining the nail. Fig. 13 represents a section on line $z'-z'$, Fig. 12. Fig. 14 represents a bottom view of a heel in which the nails have been driven.

The same letters of reference indicate the same parts in all the figures.

In the drawings, a represents a vertical pillar, to which is pivoted, at a' , a frame or head, b , supporting at its opposite ends the gangs of nail-holders c and the gangs of drivers d , with their driver-bars e . The head b is adapted to rotate horizontally and move the gangs into and out of their operative positions. Each gang of nail-holders c is supported between two vertical guides, f , rigidly attached to the head b , and each gang of drivers is supported by a plate, g , which is adapted to slide on the

guides f , the driver-bar e of each gang of drivers projecting above the head b , and being provided with a spring, h , which is adapted to raise the gang of drivers above the gang of nail-holders, as shown at the right hand of Fig. 1, so that the attendant can readily insert the nails into the rear gang of holders, the latter being unobstructed by the drivers. 50

i represents an arm rigidly attached to the pillar a , and provided at its outer end with upwardly-projecting bearings j , in which is journaled a shaft, k , carrying a cam, l , and a clutch-pulley, m , for the belt that rotates said shaft. The cam l , which depresses the driver-bar and forces the nails through the nail holders, bears upon an intermediate driver-bar, o , resting upon the upper end of the driver-bar proper and held in yielding contact with the 65 cam by a spring, p .

q represents an inclined surface formed on the arm i at one side of the bar o . Said surface is adapted to depress each driver-bar e when it is moved toward its operative position by the rotation of the head b , and thus depress the drivers d nearly to the nail-holders, so that the downward movement of the drivers by the cam l does not require to be of such extent as it would without the surface q , and the nails 70 are therefore more rapidly driven. The holder or frame of each gang of nail-holders is provided with a rearwardly-extending arm, s , which has a spring bolt or catch, s' , adapted to engage automatically with an arm, t , rigidly attached to the pillar a , and lock the head 75 b when the nail-holders and drivers are in their operative position.

Each gang of nail-holders is composed of a series of blocks, u , each having a longitudinal 85 nail-receiving aperture, v , and spring-jaws w to grasp the nail with a yielding pressure, as more fully described hereinafter. The blocks u of each gang are secured to a frame composed of plates A , rigidly connected by suitable bolts and provided with diverging slots B , in which the blocks u are placed, said blocks being movable in the slots, so that they can 90 be adjusted to hold nails for heels of different

sizes. Each block is reduced in size where it enters the slots, and is threaded at its upper end and provided with a jam-nut, C, adapted to secure the block to its frame.

5 The jaws *w w* are arranged to press inwardly against the sides of the nail, and one of said jaws is beveled at the upper portion of its inner edge, as shown in Fig. 11, so that in case the nail is inserted diagonally, as shown in the 10 last-named figure, the beveled edge will partially turn the nail until its wider sides are parallel with the proximate edges of the lower portions of the jaws, as shown in Fig. 10. The 15 nails are thus caused always to maintain the same relation to the jaws, so that by a proper arrangement of the jaws all the nails will be driven with their wider transverse sections substantially at right angles with the surface of the heel, as shown in Fig. 14, and will therefore 20 be prevented from being turned outwardly where they are clinched.

I prefer to provide each block with a spring-jaw, D, arranged to bear against one side of the point of the nail and give the latter an inclination corresponding somewhat to the inclination of the heel, as shown in Figs. 12 and 13.

Each gang of drivers *d* is mounted on a plate, E, which is provided with a dovetail groove receiving a corresponding tongue on the plate 30 *g*, which is rigidly attached to the driver-bar *h*. The plate E, with its drivers, is therefore adapted to be removed from the driver-bar, so that different-sized gangs can be employed. I do not limit myself, however, to the tongue and 35 groove, as any suitable means for detachably connecting the drivers to the driver-bar may be employed without departing from the spirit of my invention.

The boot or shoe holding last G is supported 40 on a vertical screw-shaft, H, which is journaled in a standard, I, and rotated by bevel-gears J K and a hand-wheel, L, to raise and lower the last, which is prevented from rotating by a fixed guide, L', projecting into a socket, 45 M, in the last, as shown in Fig. 4. The operator is thus enabled to raise the last and press the heel against the gang of nail-holders, as shown in Fig. 1.

O represents a toe-piece mounted on a bar, 50 P, which is movable in and out of a socket, P', in the last by means of a rack, R, and pinion Q. The toe-piece can therefore be moved toward or from the body of the last to adapt the same to different lengths of boots and shoes.

55 In the operation of the machine an attendant places the nails in the unobstructed rear gang of holders while those in the forward gang are being inserted into the heel. The two gangs of holders and drivers are preferably so arranged that each will insert their nails at different points from the other, so that both gangs can be used on the same heel, one being used for longer nails than the other, the longer nails being left projecting to afford means for 65 attaching the finishing or top lift.

Having thus described my invention, I claim—

1. In a heel-ing-machine, the combination of a gang of nail-holders supported by a rotary frame or head, a gang of drivers adapted to move vertically in guides above said nail-holders, and normally elevated above the nail-holders by a spring or its equivalent, a cam to depress the driver-bar and force the drivers into the nail-holders, and a fixed inclined surface 75 adapted to partially depress the driver-bar before it is acted on by the cam, as and for the purpose specified.

2. In a heel-ing-machine, the combination of a series of gangs of nail-holders supported by a rotary frame or head, a last to support the boot or shoe, a series of gangs of drivers corresponding with the gangs of nail-holders and elevated above the same by springs, so that normally the nail-holders will be unobstructed 80 by the drivers, a fixed inclined surface adapted to partially depress the driver-bar of each series before said bar comes into operative position over the last, and a cam adapted to further depress the driver-bar when the same 85 comes to its operative position, as set forth.

3. In a heel-ing-machine, the combination of a gang of nail-holders with a frame for said holders, constructed to permit of the adjustment of each of said holders radially in and out, and 95 clamping devices for securing the holders in adjusted position, whereby the holders are adapted to be set for placing the nails uniformly in heels of different sizes, substantially as described.

4. The combination of the gang-holding frame composed of the connected top and bottom plates A A, having radial slots B, and the nail-holders adjustable in said slots, as set forth.

5. The nail-holders, each composed of a block, *u*, reduced in size where it enters the slots in the holding-plates and screw-threaded at its upper end for the accommodation of a nut, and having a longitudinal nail-receiving aperture, *v*, and spring-jaws *w w*, substantially as described.

6. The combination, with a nail-holder, of the spring-jaw D, extending down under the said holder and arranged to bear against one side of the point of the nails, so as to give the nail an inclination corresponding somewhat to the inclination of the outside of the heel, substantially as described.

In testimony whereof I have signed my name to this specification, in the presence of two subscribing witnesses, this 9th day of August, A. D. 1881.

WILLIAM J. HEFFERNAN.
